Specification of Letters Patent.

Patented May 8, 1917.

Application filed November 24, 1916. Serial No. 133,175.

To all whom it may concern:

Be it known that I, EMIL M. HENNIES, a citizen of the United States, residing at Donnellson, in the county of Lee and State of Iowa, have invented certain new and useful Improvements in Carriers, of which the following is a specification.

This invention relates to an improved receptacle for carrying wood, water or other articles, and the principal object of the invention is to provide a device which may be used for carrying material from one place to another, the receptacle being so constructed that it may be used either in an upright or in a horizontal position, an improved type of handle being connected with one end and a bail connected with the sides of the receptacle and releasably held in an adjusted position.

Another object of the invention is to provide a receptacle so constructed that it will be water tight thus preventing leakage of water or dust when the device is in use.

This invention is illustrated in the accompanying drawings, wherein:—

Figure 1 is a view showing the improved receptacle in side elevation, and in a position for carrying water,

Fig. 2 is a view showing the device in side elevation and in a position for carrying wood,

Fig. 3 is a longitudinal sectional view through the device, in the position shown in Fig. 2,

Fig. 4 is a fragmentary view showing a modified form of handle for the end of the receptacle.

The receptacle 10 which may be used either in the position shown in Fig. 1 or in the position shown in Figs. 2 and 3 is formed of sheet metal and is braced by the side strips 11 and 12, end strips 13 and an end plate 14, the strips and plate being connected to provide a frame positioned about the receptacle and secured by means of the rivets 15. The handle 16 which is secured to the plate 14 is used for carrying the receptacle when used as a wood carrier and when so used, the bails 17 will be swung from the position shown in Fig. 1 out of engagement with the clips 18 and moved into engagement with the clip 19 secured to the handle 16. If so desired, the handle may be constructed as shown in Fig. 4, in which case, the forward end will be extended and bent to provide the clip 16' cor-

responding to the clip 19. After the receptacle is filled with wood, it being placed in the position shown in Fig. 2 while filling, it may be lifted by means of the handle 16 and carried into the house, it can then be either set down in the position shown in this figure or it may be turned to the position shown in Fig. 1 with the bail still engaged by the clip 19. If used for carrying water or other articles, the bail 17 will be swung upwardly and engaged by the clips 18 and can then be filled and carried by means of the bail. This receptacle will not leak as the only openings formed therein are provided for the rivets 15 which are positioned adjacent the upper edge of the receptacle and therefore even if these rivets were not secured tightly in place, there would be no danger of leakage. The frame braces this receptacle and will greatly strengthen it, preventing it from breaking or bulging out. It will thus be seen that a very serviceable receptacle has been provided for the uses specified.

What is claimed is:—

1. A receptacle, a frame secured about said receptacle and including an end plate, a handle secured to the end plate, a clip extending from said handle, a bail secured to said frame for pivotal movement and engaged by said clip when swung to extend longitudinally of the receptacle, and clips carried by said frame for engaging said bail when swung to extend transversely of said receptacle.

2. A receptacle, a frame positioned about said receptacle and including side strips, end strips connecting said side strips, and an end plate connecting said side strips, a handle carried by said end plate and extending transversely of the receptacle and having an extension forming a clip, a bail pivotally connected with said frame intermediate the length of said receptacle and engaged by said clip when swung to extend longitudinally of the receptacle, and clips carried by the frame for engaging the bail to hold the same in an upright position.

3. A receptacle, a frame positioned about the receptacle for bracing the same, a handle carried by said frame and extending transversely of the receptacle at one end thereof, a clip extending from the handle, and a bail pivotally connected with the frame and engaged by the clip when swung to extend longitudinally of the receptacle.

4. A receptacle, a bracing frame positioned about the receptacle, a bail pivotally mounted intermediate the length of the receptacle, means for releasably holding the bail in an upright position, a handle extending transversely of one end of said receptacle, and means extending from the handle for engaging the bail to releasably hold the same extended longitudinally of the receptacle.

5. A receptacle, a handle at one end of said receptacle, a bail adjustably mounted intermediate the length of said receptacle and

extending out from the receptacle when in an operative position and extending longitudinally of the receptacle when in an inoperative position, and means extending from the handle for releasably holding the bail in an inoperative position.

In testimony whereof I affix my signature 20 in presence of two witnesses.

EMIL M. HENNIES.
